(57) **CLAIM**

The ornamental design for a combined sump water discharge and stormwater management device, as shown and described.

DESCRIPTION

The FIGURE is a side elevation view showing my new design.

The combined sump water discharge and stormwater management device is shown with a symbolic break in its length. The appearance of any portion of the article between the break lines forms no part of the claimed design.

The broken line in the FIGURE depicts environment and forms no part of the claim.
